UNITED STATES PATENT OFFICE.

FERDINAND A. PFEIFER, OF SPRINGFIELD, OHIO, ASSIGNOR, BY MESNE ASSIGNMENTS, TO THE SAMSON MANUFACTURING COMPANY, OF SPRINGFIELD, OHIO, A CORPORATION OF OHIO.

WHEELED TOY.

Application filed November 8, 1924. Serial No. 748,568.

To all whom it may concern:

Be it known that I, FERDINAND A. PFEIFER, a citizen of the United States, residing at Springfield, in the county of Clark and State of Ohio, have invented certain new and useful Improvements in Wheeled Toys, of which the following is a specification, reference being had therein to the accompanying drawing.

10 This invention relates to wheel toys and more particularly to a wheeled toy adapted to support and to be operated by a child.

One object of the invention is to provide a device of this kind which will be 15 of a strong durable character; which may be easily operated and controlled, and which may be produced at a low cost.

20 A further object of the invention is to provide such a device in which the steering axle will be held against turning movement until positive pressure is applied thereto and will tend to automatically return to its normal position after it has been turned.

25 A further object of the invention is to provide such a device in which the driving mechanism will be so arranged as to produce a minimum of frictional resistance or binding of parts in the operation of the 30 device.

35 A further object of the invention is to provide a device of this kind with a strong rigid wheel, including the hub, which may be manufactured at a low cost.

40 Other objects of the invention will appear as the device is described in detail.

In the accompanying drawings Fig. 1 is a top plan view of a device embodying my invention, partly in section; Fig. 2 is a section taken on the line 2—2 of Fig. 1 looking in the direction of the arrow; Fig. 3 is a sectional detail view taken on the line 3—3 of Fig. 1, showing the connection between one of the wheels and the steering axle; Fig. 4 is a sectional view taken centrally through one of the wheels; Fig. 5 is a side elevation of a device embodying my invention with the steering axle in section and the rear wheel partly broken away; Fig. 6 is a section taken on the line 6—6 of Fig. 5 showing the operating lever in elevation; Fig. 7 is a bottom plan view of the seat and a portion of the frame; Fig. 8 is a front elevation of a portion of the device showing the connection between the steering 55 axle and the frame; Fig. 9 is a view similar to Fig. 3 showing the front wheels provided with roller bearings; and Fig. 10 is a section on the line 10—10 of Fig. 4.

In these drawings I have illustrated one embodiment of my invention and have shown the same as comprising a frame consisting of a single bar and supported by three wheels but it will be understood that this particular embodiment has been chosen 60 for the purposes of illustration only and that the invention may take various forms and may be embodied in vehicles of various kinds without departing from the spirit 65 thereof.

In that particular form here shown the device comprises a narrow elongated frame 1 which is supported at its front end by an axle 2 pivotally connected thereto and provided at its ends with wheels 3. At its rear end the frame is supported by a single driving wheel 4 with which is associated 70 suitable operating mechanism for propelling the vehicle. The axle 2 may be connected with the frame in any suitable manner but I prefer that the connection should be such that the weight of the frame and the load thereon will resist the turning movement of the axle about its vertical axis 75 and will tend to restore the axle to its 80 normal position, at right angles to the frame, after it has been turned in steering the vehicle. As here shown the frame 1 consists of a single flat bar of metal arranged on edge, in a vertical plane, and the 85 forward end portion of which is twisted about a longitudinal axis so that its greatest width will extend transversely to the plane of the body portion of the frame bar, as shown at 5. This transverse portion of 90 the frame is provided in its lower surface with an elongated recess or channel 6 which is preferably formed by bending or curving the end portion 5 of the frame bar about a longitudinal axis. The axle 2 has 95 a part shaped to fit within this recess when the axle is at right angles to the frame and, as here shown, the central part of the axle is of increased vertical width to provide 100 the same with a projection 7, the upper surface of which is curved to fit within the curved recess in the end of the frame. The 105 connection between the frame and the axle

is such as to permit the frame to have a limited vertical movement with relation to the axle so that when force is applied to the axle in a direction to turn the same 5 the projection 7 thereof will engage the converging walls of the recess 6 in the frame with a cam action and will force the frame upwardly against the weight of the load thereon and as soon as the turning force 10 has been relieved the weight on the frame will tend to restore the axle to its normal position. In the present instance the frame is connected with the axle by means of a pivot pin or king bolt 8 which is slidably 15 mounted in a vertical opening in the axle and the upper end of which is rigidly secured to the frame member. Preferably the upper end of the pivot pin is reduced, as shown at 9, to extend through an opening formed centrally of the recessed portion 20 of the frame and the upper end of this reduced portion is upset or riveted to secure the pin to the frame. The lower end of the pivot pin is provided with a stop, such 25 as a transverse pin 10, to limit its upward movement.

The ground wheels which support the axle 2 and which are shown at 3 may be secured to the respective ends of the axle 30 in any suitable manner but, as here shown, each end of the axle is provided with a longitudinal recess 12 adapted to receive the end of a pin or spindle 13 which extends through a hub 14 of the wheel and is provided at its outer end with a head 15 to retain the wheel thereon. This pin or spindle is first passed through the hub and then inserted in the recess 12, in which it is rigidly secured in any suitable manner, as by 35 means of a cotter pin 16. The hubs 14 of the front wheels may be provided with hub caps 62^a, which give the hubs a finished appearance and which, in the present instance, are permanently attached to the respective 40 hubs and provided with openings through which the spindles may be removed. The hubs 14 may, if desired, be provided with bearing rollers 63, as is shown in Fig. 9. If desired, the recess 12 may be arranged 45 at a slight angle to the length of the axle so as to incline or tilt the wheels, as shown in Fig. 2. The ends of the axle may be enlarged, as shown at 17, and given a shape 50 to correspond more or less to the steering knuckle of an automobile.

The driving wheel 4, may be of any suitable character and may be connected with the rear end of the frame in any desired manner. In the present instance the driving wheel is of similar construction to the steering wheels and is carried by a transverse axle or shaft 19 extending through the hub 64 thereof and supported at its ends 60 in the arms 20 and 21 of a yoke 22 which is rigidly secured to the bar or frame 1.

The axle 19 is held in the arms 20 and 21 by cotter pins 19^a which hold the rear wheel assembly in position in the yoke. As here shown, the yoke is provided with a forwardly extending web or bracket 24, which 70 is rigidly secured to the end of the frame by means of rivets or bolts 25. A sprocket wheel 26 is rigidly secured to the driving wheel by connecting members such as rivets 65 which pass through the sprocket and ears 66 formed by pockets 67 in the hub 64. The sprocket 26 is connected by means of a sprocket chain 27 with a second sprocket wheel 28, of larger diameter, which is mounted on a stud shaft 29 mounted in the arm 20 of the yoke 22 and extending inwardly therefrom, so that the sprocket wheels and chain are arranged between the arm of the yoke and the wheel. The sprocket wheel 28 is connected by means of a connecting rod or pitman 30 with an actuating device, such as a lever 31, which is mounted on the frame 1 near the forward end thereof. The actuating lever 31, as here shown, comprises two bars rigidly secured 80 one to the other near their ends and having their lower portions spaced apart to receive between them the frame bar 1 and the connecting rod 30. A bolt 32 extending through the two parts of the lever and the frame pivotally connects the lever with the frame, and a bolt 33 extends through the two parts of the lever and the connecting rod to pivotally connect these members. The lever is preferably provided in its lower portion with two or more openings 34 to receive the bolt 33 so as to vary the distance 90 between the pitman and the axis of the lever, thus varying the length of the stroke of the operating lever and enabling the speed 100 to be varied. The connecting rod 30 is attached to the lever 31 directly beneath the frame bar 1 and is connected with the sprocket wheel 28 by means of a pivot pin or wrist 35 which extends inwardly therefrom, 105 thus locating the pivotal connection between the connecting rod and the sprocket wheel and close to the driving wheel. This causes the connecting bar to extend at a slight angle to the frame and reduces to a minimum 110 the tendency of the connecting rod to bind at its points of connection with the lever and the sprocket wheel. The arm 20 of the yoke is of such width that it will extend upwardly above the upper stretch of the 115 sprocket chain 27 and will constitute a guard for that chain. If desired, a mud guard 36 may be secured to the forward end of the yoke 22 and curved upwardly and rearwardly above the driving wheel.

Mounted on the frame 1 between the operating lever 31 and the driving wheel is a seat 37. As here shown, this seat is carried by a bracket 38 provided with a longitudinal groove or channel 39 in its lower side 120

to receive the upper edge of the frame bar 1 and has near its forward end a depending web or bracket 40 overlapping the frame bar 1 and adapted to be secured to that bar by means of a suitable connecting device, such as a bolt 41 which may be inserted through any one of a series of openings 42 in the frame. This connection between the seat and the frame is such as to permit the seat to be readily adjusted from one position to another and to hold the same rigidly in its adjusted position and to effectually prevent the same from tilting on the narrow frame member.

The seat and operating lever 31 are so arranged with relation to the steering axle that the occupant of the seat may place his feet against the axle 2 on opposite sides of the frame, the axle being provided with foot plates or pads 43, and may grasp the lever 31 to operate the machine. The lever 31 is provided with a cross bar 44 to provide a convenient hand grip for the operator. This cross bar may be secured to the upper end of the lever in any suitable manner but, in the present instance, I have employed a connecting bracket 45 having a depending web 46 extending between the upper ends of the two parts of the lever, which are spaced apart to receive the same, and rigidly secured thereto. The upper portion of the bracket comprises a horizontal channel 47, preferably curved about a transverse axis, and adapted to receive and fit about the cross bar 44. The upper edges of the channel extend slightly above the horizontal center of the cross bar. This bracket is preferably formed of a malleable casting and is cast with the side walls of the channel spaced apart throughout their width a distance sufficient to permit the insertion of the cross bar. After the cross bar has been inserted the upper edges of the channel walls are pressed about the bar so as to partially enclose the same and retain the same in the channel. Pins or rivets 48 are inserted through the channel and cross bar to hold the latter against endwise movement.

The wheels for the vehicle may be of any suitable character and, as has been stated, the front and rear wheels are preferably similar in construction. I prefer, however, to employ the disk type of wheel and I have here shown a disk wheel which is very inexpensive to manufacture and which is of a very strong durable character. In this wheel the hub 14 is provided with a circumferential flange 49 arranged approximately midway between the ends thereof and adapted to form a support for a disk 50 of sheet metal having a central opening to enable the hub to be inserted through the same. A clamping ring 51 fits about the hub on that side of the disk 50 opposite the flange 49 and is rigidly secured to the flange by

means of bolts or rivets 52 extending through the clamping ring, disk and flange. The disk 50 is provided at its outer edge with a circumferential rim 53 which may be of any suitable character but is here shown as channeled to receive a tire 54. The rim is preferably substantially semi-circular in cross section and is formed separately from the disk 50. To enable the rim to be easily and rigidly secured to the disk the circumferential portion of the disk is slit at intervals and the alternate portions thereof are bent laterally in opposite directions, as shown at 55 and 56. When the projections 55 and 56 are bent laterally 80 those on one side of the disk are bent back to a position at substantially right angles to the plane of the disk so that the rim may be slipped onto the same and after the rim is in position the projections are pressed forwardly so that they will fit snugly and tightly about the curved inner surface of the rim. Preferably the other series of projections are given a curved shape when formed so that they will fit about the surface 85 of the rim. By thus initially shaping the second series of projections they form stops and facilitate the positioning of the rim on the disk.

If desired, the device may be provided 95 with a carrier which may serve either as a bundle carrier or an auxiliary seat. As here shown, the carrier is in the form of a shallow receptacle 57 rigidly secured to the upper end of a supporting bracket 58, the lower end of which is provided with a portion 59 overlapping the frame bar 1 and adapted to be secured thereto by means of a bolt 60. The lower end of the bracket is provided in the rear of the bolt 60 with a transverse lug 61 which rests upon the upper edge of the frame bar, and is further provided in front of the bolt with a forwardly extending projection or foot 62 which rests on the transverse portion of the frame bar near its forward end, thus forming a very rigid support for the carrier on the frame, and enabling the same to be quickly and easily removed from or placed 105 in position on the frame.

The construction and operation of the vehicle will be readily understood from the foregoing description and it will be apparent that I have provided a device of this kind which is of a very strong rigid construction, very simple in its construction and of such a character that it can be manufactured and assembled at a low cost. Because of the arrangement of the operating mechanism the operation of the device is easy, there being practically no tendency of the several parts of the driving mechanism to bind or to cause undue friction or resistance. The connection between the steering axle and the frame tends to hold this axle normally in 110 115 120 125 130 135

a position at right angles to the frame and prevents the same from wobbling or from turning until positive force is applied thereto, thus making the device very easy to steer. The seat and operating mechanism are adjustable to accommodate the same to children of different sizes and, further, the construction is light in weight so that it can be easily handled by a child.

10 While I have shown and described one embodiment of my invention I wish it to be understood that I do not desire to be limited to the details thereof as various modifications may appear to a person skilled 15 in the art.

Having now fully described my invention, what I claim as new and desire to secure by Letters Patent, is:

20 1. In a device of the character described, a longitudinal frame, a seat carried by said frame, a driving wheel supporting one end of said frame, means for actuating said driving wheel, an axle pivotally connected between its ends with the other end of said frame, and wheels carried by the respective ends of said axle, said axle and said frame having cooperating parts controlled by the weight on said frame to resist the movement of said axle about its pivotal connection with said frame.

25 2. In a device of the character described, a longitudinal frame, a seat carried by said frame, a driving wheel supporting one end of said frame, means for actuating said driving wheel, an axle pivotally connected between its ends with the other end of said frame, and wheels carried by the respective ends of said axle, said end of said frame being capable of vertical movement relative to said axle and said axle having a part arranged to impart vertical movement to said end of said frame when said axle is moved about its pivotal connection with said frame.

30 3. In a device of the character described, a longitudinal frame, a seat carried by said frame, a driving wheel supporting one end of said frame, means for actuating said driving wheel, an axle pivotally connected between its ends with the other end of said frame, and wheels carried by the respective ends of said axle, said axle and said frame having cooperating cam shaped parts controlled by the weight on said frame to resist the movement of said axle about its pivotal connection with said frame.

35 4. In a device of the character described, a longitudinal frame, a seat carried by said frame, a driving wheel supporting one end of said frame, means for actuating said driving wheel, an axle pivotally connected between its ends with the other end of same frame, and wheels carried by the respective ends of said axle, said end of said frame being capable of vertical movement relative to

said axle and having a recess in its lower surface, and said axle having a part arranged to enter said recess and so shaped that the movement of said axle about its axis will impart vertical movement to the 70 end of said frame.

5. In a device of the character described, a driving wheel, an axle, wheels carried by said axle, a frame supported at one end by said driving wheel and at the other end 75 by said axle, the last mentioned end of said frame having a recess provided with upwardly converging walls and said axle having a part extending into said recess, a pivot pin connecting said frame and said axle, extending through said recess and said part of said axle and arranged to permit the end of said frame to move upward relative to said axle, said part of said axle being so shaped that it will impart upward movement to said end of said frame when said axle is turned about its axis.

6. In a device of the character described, a driving wheel, an axle having an upwardly extending projection at the center 90 thereof, wheels carried by said axle, a frame comprising a flat bar arranged in a vertical plane, supported at its rear end by said driving wheel and having its front end portion turned about a longitudinal axis 95 approximately to a horizontal plane and having a recess in the lower side thereof to receive the projection on said axle, and a pivot pin connecting said front end of said frame to said axle and arranged to permit said end 100 of said frame to move upward relative to said axle.

7. In a device of the character described, a frame, an axle pivotally connected with and supporting one end of said frame, one 105 of said parts having a recess and the other of said parts having a projection extending into said recess, said end of said frame being capable of a limited upward movement with relation to said axle and said projection, and said recess being so arranged that the movement of said axle about its pivotal connection with said frame will impart upward movement to said frame, whereby said frame will resist the turning of said axle 110 and will tend to retain the same in its normal position with relation to said frame.

8. In a device of the character described, an axle, wheels carried by said axle, a narrow elongated frame having its upper edge materially lower than the tops of said wheels and having its forward end supported by and pivotally connected with said axle between the ends thereof, a driving wheel, means for connecting said driving wheel with the rear end of said frame, a seat carried by said frame, and means mounted on said frame for actuating said driving wheel.

9. In a device of the character described,

- an axle, wheels carried by said axle, a narrow elongated frame having its upper edge materially lower than the tops of said wheels and having its forward end supported by and pivotally connected with said axle between the ends thereof, a yoke secured to the rear end of said frame, a driving wheel mounted in said yoke, a seat carried by said frame, an actuating member 5 mounted on said frame between said seat and said axle, and means for operatively connecting said actuating member with said driving wheel.
10. In a device of the character described, an axle, wheels carried by said axle, a narrow elongated frame having its forward end supported by and pivotally connected with said axle, a yoke secured to the rear end of said frame, a driving wheel mounted 15 between the arms of said yoke, a sprocket wheel secured to said driving wheel, a second sprocket wheel mounted on one arm of said yoke and arranged between said arm and said sprocket wheel, a sprocket chain 20 extending about said sprocket wheels, a lever mounted on said frame, and a connecting rod connected at one end with said lever and connected at its other end with said second sprocket wheel, the last mentioned end 25 of said connecting rod being arranged between said second sprocket wheel and said driving wheel.
11. In a device of the character described, an axle, wheels carried by said axle, a narrow elongated frame having its forward end supported by and pivotally connected with said axle, a yoke secured to the rear end of said frame, a driving wheel mounted 30 between the arms of said yoke, driving mechanism for said wheel comprising a rotatable member mounted on one arm of said yoke between said arm and said driving wheel and having an inwardly extending wrist pin, an operating lever pivotally 35 mounted on said frame and extending beneath the same, a connecting rod pivotally connected at one end with the lower end of said lever and having its other end mounted on said wrist pin.
12. In a device of the character described, a flat bar arranged on edge and constituting the frame of said device, an axle pivotally connected to the forward end of said bar, wheels carried by said axle, a yoke rigidly secured to the rear end of said bar, a driving wheel mounted between the arms of said yoke, an actuating member mounted 45 on said bar and operatively connected with said driving wheel, and a seat mounted on said bar in the rear of said actuating member.
13. In a device of the character described, a flat bar arranged in a vertical plane and constituting the frame of said device, said 50 bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 55 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 60 said rotatable member, and a seat mounted on said bar in the rear of said lever.
14. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 65 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 70 said rotatable member, and a seat mounted on said bar in the rear of said lever.
15. In a device of the character described, a flat bar arranged on edge and constituting the frame of said device, an axle supporting the forward end of said bar and pivotally connected therewith, wheels carried by said axle, a yoke rigidly secured to the rear end of said bar, a driving wheel mounted 75 between the arms of said yoke, an actuating device mounted on said bar and operatively connected with said driving wheel, and a seat comprising a bracket having a longitudinal channel in the lower side thereof to receive the upper edge of said bar and having a part overlapping a vertical face of said bar, and means for rigidly securing said part to said bar.
16. In a device of the character described, a narrow elongated frame, an axle supporting the forward end of said frame and pivotally connected therewith, wheels carried by said axle, a driving wheel supporting the rear end of said frame, a seat 80
17. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 85 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 90 said rotatable member, and a seat mounted on said bar in the rear of said lever.
18. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 95 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 100 said rotatable member, and a seat mounted on said bar in the rear of said lever.
19. In a device of the character described, a flat bar arranged on edge and constituting the frame of said device, an axle supporting the forward end of said bar and pivotally connected therewith, wheels carried by said axle, a yoke rigidly secured to the rear end of said bar, a driving wheel mounted 105 between the arms of said yoke, an actuating device mounted on said bar and operatively connected with said driving wheel, and a seat comprising a bracket having a longitudinal channel in the lower side thereof to receive the upper edge of said bar and having a part overlapping a vertical face of said bar, and means for rigidly securing said part to said bar.
20. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 110 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 115 said rotatable member, and a seat mounted on said bar in the rear of said lever.
21. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke rigidly secured to the rear end of said bar, a driving wheel mounted 120 between the arms of said yoke, an actuating device mounted on said bar and operatively connected with said driving wheel, and a seat comprising a bracket having a longitudinal channel in the lower side thereof to receive the upper edge of said bar and having a part overlapping a vertical face of said bar, and means for rigidly securing said part to said bar.
22. In a device of the character described, a narrow elongated frame, an axle supporting the forward end of said frame and pivotally connected therewith, wheels carried by said axle, a driving wheel supporting the rear end of said frame, a seat 125
23. In a device of the character described, a flat bar arranged in a vertical plane and constituting the frame of said device, said bar having its forward end twisted about a longitudinal axis and extending at substantially right angles to the plane of said bar, an axle supporting said end of said bar and pivotally connected therewith, wheels carried by said axle, a yoke having a part overlapping the rear end of said bar and rigidly secured thereto, a driving wheel mounted 130 between the arms of said yoke, operating mechanism for said driving wheel comprising a rotatable member mounted on said yoke between one of the arms thereof and said driving wheel and operatively connected with said driving wheel, an operating lever pivotally mounted on said bar, a connecting rod connecting said lever with 135 said rotatable member, and a seat mounted on said bar in the rear of said lever.

6

mounted on said frame, a lever pivotally mounted on said frame between said seat and said axle, and operatively connected with said driving wheel, a bracket rigidly secured to the upper end of said lever and having a channel extending transversely to said lever, and a cross bar seated within said channel, the side walls of said channel extending above the horizontal center of said cross bar and fitting snugly about the same.

17. In a device of the character described, a narrow elongated frame, an axle supporting the forward end of said frame and pivotally connected therewith, wheels carried by said axle of such a diameter that they extend materially above said frame, a driving wheel supporting the rear end of said frame, an actuating device mounted on said frame and operatively connected with said driving wheel, a seat mounted on said frame, and a carrier mounted on the forward portion of said frame and arranged above said axle.

18. In a device of the character described, a narrow elongated frame, an axle supporting the forward end of said frame and pivotally connected therewith, wheels carried by said axle, a driving wheel supporting the rear end of said frame, an actuating device mounted on said frame and operatively connected with said driving wheel, a seat mounted on said frame, and a car-

rier comprising a supporting bracket having a part overlapping the forward portion of said frame, and a bolt to secure said part to said frame, said bracket having parts arranged in the front and to the rear of said bolt and engaging said frame to hold said bracket against movement about the axis of said bolt.

19. In a device of the character described, a narrow elongated frame, a driving wheel supporting the rear end of said frame, an axle supporting the forward end of said frame and pivotally connected therewith, wheels arranged at the respective ends of said axle, each of said wheels comprising a hub, a spindle journaled in said hub and having means for retaining said hub thereon, and means for rigidly securing said spindle to the adjacent end of said axle.

20. In a device of the character described, a wheel, the hub of which is provided with pockets forming ears, and a sprocket wheel attached to said ears.

21. In a device of the character described, a wheel the hub of which is provided with pockets forming ears, a sprocket wheel, and connecting means passing through said ears and sprocket wheel.

In testimony whereof, I affix my signature hereto.

FERDINAND A. PFEIFER.
